ROLLER BIT

George G. Harrington, Houston, Tex., assignor to
Need Roller Bit Company, Houston, Tex., a corporation of Texas

Application March 7, 1932, Serial No. 597,316

7 Claims. (Cl. 255—71)

This invention relates generally to deep well drilling apparatus and specifically to roller bits.

It has for its object the provision of a new and improved bit embodying a few large roller cutters constructed and arranged to traverse an area approximately equal to the transverse area of the head, and to efficiently cut a straight hole; the bit head and cutter supporting element being such that the cutters and supporting elements 10 may be quickly and easily inserted in and removed from the head as a unit.

The preferred embodiments of the invention are illustrated by the accompanying drawings, of which Fig. 1 is a partly sectional elevation; Fig. 2, a partly sectional elevation at an angle to Fig. 1; Fig. 3, a bottom plan view; Fig. 4, a fragmentary view illustrating a one piece center cutter; and Figs. 5, 6 and 7, views similar to Figs. 1, 2 and 3, respectively, and illustrating 20 a modification.

In Figs. 1, 2 and 3, the bit head is indicated at 1. It may be provided with internal threads 2 for connection to a conventional drill stem, not shown. It has three depending bearing projections 3, 4 and 5, having downwardly opening slots 6, 7 and 8, respectively. Extending upwardly from each of the slots is a bolt opening. The bolt openings of projections 4 and 5 are indicated at 9 and 10. In the center of the head is a post 20 opening 11.

The cutter support is indicated at 12. It has a post 13 to fit in the opening 11, and three radial pins 14, 15 and 16 to fit in slots 6, 7 and 8. Connected to the pins 14, 15 and 16 are bolts 17, 18 and 19 that extend upwardly in the bolt openings and are held therein by nuts 20, 21 and 22. The post 13 is held in the opening 11 by a nut 23.

The pins 14, 15 and 16 are radial and at approximately the same angle to each other. All 40 of the pins are inclined upwardly toward the periphery of the head, the pins 14 and 15 being inclined more than the pin 16. Upon the pins 14 and 15 are substantially cylindrical roller cutters 24 and 25 that project from the periphery 45 of the head and travel in approximately the same cutting path. Upon the pin 16 is a substantially frusto conical cutter that may be made in two sections 26 and 27, as shown by Figs. 1 and 3, or in one piece 28, as shown by Fig. 4. This cutter has its base end outermost and travels in a cutting path extending approximately from the cutting path of the cutters 24 and 25 to the longitudinal axis of the head.

The support, and the cutters thereon and bolts 50 connected thereto, may be inserted in the head 1

as a unit. The bolts will enter the bolt openings, the post the post opening, and the pins the pin slots. The nuts 20, 21, 22, and 23 may then be applied to the bolts and post to lock the unit in place. When it is desired to remove the cutters from the head, the support with the cutters thereon and bolts connected thereto may be removed from the head as a unit, after removal of the nuts 20, 21, 22, and 23.

In the embodiments shown by Figs. 5, 6 and 7, 65 the post 13 and bolts 17, 18 and 19 have been omitted, the cutter pins being welded in the pin slots, as indicated at 29, 30 and 31.

I claim:

1. A drill bit having a head; three cutter pins 70 mounted radially in said head at substantially the same radial angle to each other and inclined upwardly toward the periphery of said head; roller cutters on two of said pins, projecting outwardly beyond the periphery of said head, and 75 traveling in substantially the same cutting path; and a cutter on the other of said pins arranged to travel in a cutting path extending substantially from the cutting path of said two cutters to the longitudinal axis of the head. 80

2. A drill bit having a head; three cutter pins mounted radially in said head at substantially the same radial angle to each other, and inclined upwardly toward the periphery of said head; two cylindrical cutters on two of said pins, projecting 85 outwardly beyond the periphery of said head, and traveling in substantially the same cutting path; and a substantially frusto-conical cutter on the other of said pins, arranged with its base end outermost and to travel in a cutting path extending substantially from the cutting path of said cylindrical cutters to the longitudinal axis of the head. 90

3. A drill bit having a head; three cutter pins mounted radially in said head at substantially 95 the same radial angle to each other, and inclined upwardly toward the periphery of said head, two of said pins being inclined upwardly more than the other of said pins; cutters on said two pins projecting outwardly beyond the periphery of 100 said head and traveling in substantially the same cutting path; and a cutter on the said other of said pins and traveling in a cutting path extending substantially from the cutting path of said two cutters to the longitudinal axis of the head. 105

4. A drill bit having a head; three cutter pins mounted radially in said head at substantially the same radial angle to each other, and inclined upwardly toward the periphery of said head, two of said pins being inclined upwardly more than 110

the other of said pins; substantially cylindrical cutters on said two pins projecting outwardly beyond the periphery of said head and traveling in substantially the same cutting path; and a 5 substantially frusto-conical cutter on the said other of said pins, arranged with its base end outermost, and traveling in a cutting path extending substantially from the cutting path of said two cutters to the longitudinal axis of the 10 head.

5. A drill bit head having a central post opening and three depending bearing projections at substantially equal distances apart, each of said 15 projections having a downwardly opening slot and a bolt opening extending upwardly from said slot; a cutter support having a post in said post opening, and three cutter pins projecting upwardly and outwardly into said slots; roller cutters on 20 said pins; said support and cutters being slideable into said head as a unit; and means to hold said post and bolts in said openings.

6. A drill bit having a central post opening and three depending bearing projections at substantially equal distances apart, each of said projections having a downwardly opening slot; a cutter support having a post in said post opening, and three cutter pins projecting upwardly and outwardly into said slots; roller cutters on said pins; said support and cutters being slideable into said head as a unit; and means to hold said post in said opening.

7. A drill bit head having three depending bearing projections at substantially equal distances apart, each of said projections having a downwardly opening slot; a cutter support having three cutter pins projecting upwardly and outwardly into said slots; roller cutters on said pins; said support and cutters being slideable into said head as a unit; and means to hold said support in said head.
